[57] CLAIM

The ornamental design for a hip cup prosthesis, as shown and described.

DESCRIPTION

FIG. 1 is a top plan view of a hip cup prosthesis showing my new design;
 FIG. 2 is a side elevation taken in the direction of arrow 2 in FIG. 1;
 FIG. 3 is a side elevation taken in the direction of arrow 3 in FIG. 1;
 FIG. 4 is a side elevation taken in the direction of arrow 4 in FIG. 1;
 FIG. 5 is a side elevation taken in the direction of arrow 5 in FIG. 1;
 FIG. 6 is a side elevation taken in the direction of arrow 6 in FIG. 1;
 FIG. 7 is a side elevation taken in the direction of arrow 7 in FIG. 1;
 FIG. 8 is a side elevation taken in the direction of arrow 8 in FIG. 1;
 FIG. 9 is a bottom plan view of FIG. 1;
 FIG. 10 is a cross-section taken on line 10-10 of FIG. 1.
